UNITED STATES PATENT OFFICE

CARL MÜNCH, OF DUREN, GERMANY

METHOD OF PRODUCING ABRASIVE PAPER AND THE LIKE

Application filed September 9, 1931, Serial No. 561,883, and in Germany September 9, 1930.

This invention relates to a method for producing abrasive paper and the like, in which cellulose ester dissolved in a solvent of low boiling point, such as alcohol, is used as binding medium for the mutual connection of the abrasive grains and with the support.

The known methods of this kind are carried out in such a manner, that first the cellulose ester solution is applied alone on to the support, whereupon the abrasive is strewn on to the applied layer whilst the same is still sticky. Consequently, these known methods are inconvenient and waste time, and on the abrasive paper produced thereby the abrasive grains are not uniformly distributed over the grinding surface and are not sufficiently embedded in the binding medium, so that the grinding surface is also not smooth. The grinding coating of the abrasive paper thus produced is as a rule subsequently provided with a further layer of cellulose ester, in order to smoothen the grinding surface. By this measure however the known processes of the kind in question are rendered still more complicated, without overcoming the objection of the irregular distribution of the grains of abrasive on the support. These inconveniences are overcome according to the invention.

The invention consists substantially in that first the cellulose ester, dissolved in a solvent, possessing a low boiling point, is mixed with the abrasive, after which the mixture thus obtained is applied in thoroughly mixed condition continually on to the circumference of a rotating cylinder and then continually brushed off from the periphery of the cylinder by means of a paper or fabric web moved in the same direction and bearing against the circumference of the cylinder so that the mixture is transferred to the paper or fabric web. The new method is much more simple than the known methods of its kind and the abrasive paper produced thereby shows a very uniform distribution of the abrasive particles on the support with proper embedding in the binding medium and consequently a very smooth surface produced without any further measures.

The article produced by the new method is preferably subsequently heated by pressing against heated surfaces, so that the strain produced in the abrasive coating by the drying of the collodion layer and warping of the article which might be caused thereby are avoided.

For carrying out the method a device illustrated diagrammatically in the only figure of the accompanying drawing is preferably employed, which consists substantially of three cylinders, *a*, *b*, *c*, the two cylinders *b*, *c* of which are arranged, rotatable in clockwise direction, side by side so that a gap *F* is left between them corresponding in width approximately to the thickness of the coating to be applied to the support, whereas the third cylinder *a* is mounted rotatable in the same direction under the cylinder *b* at a certain distance so that a passage is left the width of which corresponds to the thickness of the support. The space above the gap *F* between the cylinder *b* and the cylinder *c* provided at the top with a scraper *d*, is filled with a mixture of cellulose ester solution and granular abrasive, and at the same time the paper or fabric web *e* designed to serve as support is conducted from below over the cylinder *a* and between this cylinder and the cylinder *b*, and consequently conveyed by the cylinders *a*, *b* in the direction indicated in the drawing by the arrow. Owing to the rotating movement of the cylinders *b* and *c* a continuous effective mixing of the mixture between these cylinders takes place automatically, a portion of the mixture being continually carried along by the periphery of the cylinder *b* in the form of a thin layer *g*, the thickness of which corresponds approximately to the width of the gap *F* between the cylinders *b* and *c*. As soon as the layer *g* of mixture carried along by the periphery of the cylinder *b* arrives on the moved support *e*, it is scraped off from the cylinder *b* by this support and continually applied in a smooth layer onto the support *e*, where it rapidly dries.

I claim:

In a method of producing abrasive paper and similar articles provided with a coating,

in combination, the steps of dissolving cellulose ester in a solvent having a low boiling point, mixing the dissolved cellulose ester with an abrasive material, continuously introducing the mixture into a space between a first and a second cylinder, said space corresponding to the desired thickness of the coat-

ing, and bringing a moving paper web passing over a third cylinder in contact with the first cylinder, all the three cylinders rotating in the same direction, the mixture carried by the first cylinder being transferred to said paper web.

CARL MÜNCH.
